UNITED STATES PATENT OFFICE.

PARKER Z. BLOSER, OF COLUMBUS, OHIO, ASSIGNOR TO THE ZANER-BLOSER COMPANY, OF COLUMBUS, OHIO, A CORPORATION OF OHIO.

DESIGN FOR A PENHOLDER.

Application filed April 17, 1928. Serial No. 26,357. Term of patent 14 years.

To all whom it may concern:

Be it known that I, PARKER Z. BLOSER, a citizen of the United States, residing at Columbus, in the county of Franklin and State of Ohio, have invented a new, original, and ornamental Design for Penholders, of which the following is a specification, reference being had to the accompanying drawing, forming part thereof.

The figure shown is a perspective view of one of the pen holders, showing my new design.

I claim:

The ornamental design for a pen holder, as shown.

PARKER Z. BLOSER.
